(57) **CLAIM**

The ornamental design for a wrist cushion as shown and described.

DESCRIPTION

FIG. 1 is a front perspective view of a wrist cushion; FIG. 2 is a back perspective view thereof;

FIG. 3 is a top view thereof;

FIG. 4 is a bottom view thereof;

FIG. 5 is a front side view thereof;

FIG. 6 is a rear view thereof;

FIG. 7 is a left view thereof;

FIG. 8 is a right view thereof; and,

FIG. 9 is a perspective view of the wrist cushion of FIG. 1 shown in an alternate configuration in an environment of use.

Broken lines in FIG. 9 illustrate environmental subject matter that forms no part of the claimed design.

Jagged break lines on the wrist cushion depict a symbolic break in length and form no part of the claimed design.
